METHOD AND APPARATUS FOR FORMING SHEET METAL

Application filed December 28, 1923. Serial No. 683,206.

This invention relates to a method and apparatus for forming sheet metal articles and more particularly to the method and means for forming sharp bends across unweakened areas of sheets, such areas lying between and adjacent to larger areas which have been greatly weakened by being perforated.

As shown herein, the invention is applied to the formation of the cylindrical shell of a washing machine cylinder in which the shell is provided with integral reentrant portions forming baffles, the cylindrical portions of the shell and the sides of the baffles being provided with closely adjacent perforations.

An object of the invention is to provide a method for bending sheets which have perforated areas separated by relatively narrow unperforated strips by operating upon the unperforated portions of the sheet to form relatively sharp bends therein without distorting the perforated portions of the sheet. In forming sharp or fairly sharp bends in sheet metal, a set must be given to each bend by the application of a heavy force to the parts making the bend at the end of the bending operation. It is an object of the present invention to provide means for effectively applying the necessary pressure to the portions of the sheet at the bends at the end of the bending operation. It is very desirable in a washer cylinder that the holes in the perforated areas be indented, i. e. flanged out slightly and it is one of the main objects of the present invention to provide a method and apparatus for forming such cylinders in which the perforated sheets with indented openings may be given the desired form without distorting, flattening or ironing out the flanges or indentations surrounding the openings.

A further object of the invention is to provide a method and means by which the integral reentrant portions or baffles in the shell may be formed one at a time and portions of the cylindrical part of the shell on opposite sides of the baffles may be simultaneously formed so that after a number of operations equal to the number of baffles in the cylindrical shell a complete cylindrical shell will be formed.

With the above and other objects in view, the invention may be said to comprise the method and apparatus as illustrated in the accompanying drawings described in the following specification and specifically set forth in the appended claims, together with such variations and modifications thereof as will be apparent to one skilled in the art to which the invention appertains.

Reference should be had to the accompanying drawings forming a part of this specification in which Figure 1 is an end elevation of the forming apparatus, the parts being shown in the position where the forming operation is complete; Fig. 2 is a partial vertical section on line 2—2 of Fig. 1; Fig. 3 is a horizontal section at one end of the machine taken on line 3—3 of Fig. 1; Fig. 4 is a transverse section taken on line 4—4 of Fig. 2 and showing the position of the forming parts when the sheet is introduced; Fig. 5 is an end elevation showing the forming parts in the position they occupy at the instant when the formation of the baffle is just beginning; Fig. 6 is a fragmentary plan view showing a part of a perforated sheet from which the cylindrical shell is to be formed; Fig. 7 shows the cylindrical shell completely formed; Fig. 8 is a fragmentary section showing a small portion of the sheet on an enlarged scale, the section being taken through indented perforations.

Referring first to Figs. 6, 7 and 8 of the drawings, the sheet from which the cylinder is to be formed is designated generally by the letter S. The completed cylinder is designated generally by the letter C and the integral baffles are indicated by the letter B. The sheet S has relatively large perforated areas *a* which form the cylindrical portions of the cylindrical shell of the washer cylinder and a pair of narrow perforated areas lying between each pair of adjacent large perforated areas *a*, and forming in the completed cylindrical shell the side walls of the baffles B. Between each of the large perforated areas *a* and the adjacent narrow perforated area *b* there is a narrow transversely extending unperforated strip *c* and between the adjacent narrow perforated areas *b* there

- is a narrow unperforated strip *d*. The lines of bend at the bases and peaks of the baffles are formed along the central portions of the narrow unperforated strips *c* and *d*. The bend lines at the bases and peaks of the baffles being indicated in Fig. 6 at *m* and *n*. As shown in Fig. 8 each of the holes *e* in the sheet *S* has a surrounding short flange or indentation *f*.
- 10 In accordance with the present invention, the perforations are first formed in the sheet *S* by any suitable means, such as a punch press and the cylindrical shell is then formed from the perforated sheet *S* by successively forming portions of the sheet between forming members which have a pressure engagement with the sheet only along the unperforated strips, the sheet being bent simultaneously along the bend lines *n* and *m* to form
- 15 a rib or baffle, the metal being given a permanent set at the end of the bending operation by applying a relatively heavy pressure to the unperforated strips adjacent the bends. The cylindrical portions of the shell on oppo-
- 20 site sides of each rib or baffle are formed simultaneously between forming members with cooperating cylindrical faces which are recessed to accommodate the indentations surrounding the holes in the perforated areas
- 25 and having pressure applying edge portions which engage the sheet only along the unperforated strips *c* and along the unperforated edges *g* of the sheet.

Referring to the apparatus illustrated in Figs. 1 to 5 inclusive, the mechanism is supported upon a suitable frame or housing consisting of two end standards 1 which are joined by the stationary form 1*a* which has an upper cylindrical forming face, the axis 40 of which lies in the central longitudinal plane of the frame. The end standards of the frame have vertical guide bars 1*b* extending upwardly above the fixed form 1*a* which serve as guides for forming members which 45 will be hereinafter described.

Adjacent the bottom of the frame and extending longitudinally and centrally thereof is a drive shaft 2 adapted to be driven from any suitable source of power through a gear 50 3 fixed thereto. All of the movable parts of the forming apparatus are operated from the drive shaft 2. On the upper face of the fixed form 1*a* and centrally thereof there is an upwardly projecting rib 4 which corresponds in shape to the baffle of the cylindrical shell to be formed, the fixed cylindrical form 1*a* and baffle form 4 providing a fixed form upon which a portion of the sheet is bent by suitable movable forming members 55 into the form of one of the reentrant baffles and adjacent cylindrical portions of the shell. A sliding forming member 5 is mounted for vertical movement directly over the fixed rib 4 and is adapted to be moved into and out of engagement with the peak of the

rib 4, the sliding form 5 cooperating with the fixed rib 4 in forming the bend at the peak of the reentrant baffle. In addition to the sliding form 5 there are a pair of bodily movable pivoted forming members 6 which have lower cylindrical faces 6*a* adapted to cooperate with the fixed cylindrical form 1*a* and substantially flat faces 6*b* along their inner sides which cooperate with the side faces of the rib 4 in forming the sides of the 75 baffles. The forming members 6 are pivotally mounted upon a horizontal shaft 7 whose axis is disposed in the central vertical longitudinal plane of the frame and the shaft 7 as well as the vertically movable form 5 are 80 guided in their vertical movements between vertical guide bars 8.

At each end thereof the sliding form 5 is provided with a supporting strap 9 which has its free ends secured to opposite sides of the form 5 and is looped over the shaft 7. The straps 9 serve to support the form 5, when the movable parts are in their uppermost position, from the shaft 7 but permit relative bodily movement between the form 5 and pivoted forming members 6 during the forming operation. The pivoted forming members 6 are normally held in spread position by flat springs 10 which are secured at their ends adjacent the outer ends of the pivoted members 6 and pass over the top of the shaft 7. The pivoted forms 6 are guided in their movements toward and from the fixed form by means of rollers 11 journaled on pins 12 secured to opposite ends of the forms 6. The rollers 12 when the forming members 6 are in their uppermost position bear against the inner faces of the vertical guide bars 1*b* and engage other guide members as the pivoted forms 6 approach the fixed form in the forming operation. Vertical movements of the pivoted forms 6 are controlled by connecting links 13 which connect the opposite ends of the sliding shaft 7 with crank pins 14 secured in crank arms 15 which are keyed to the opposite ends of the drive shaft 2. The connecting links 13 lie beyond the ends of the drive shaft 2 so that during a rotation of the shaft, the shaft 7 and the forming members 6 carried thereby are given a vertical reciprocating movement. The sliding form 5 is provided with trunnions 5*a* on its opposite ends from which are suspended hook links 16, the lower hooked ends of which engage with half eccentrics 17 made integral with the crank arms 15 on the inner sides thereof. The eccentrics 17 serve to impart an additional movement to the sliding form 5 during the final portion of the forming operation. Means are provided to impart an inward swinging movement to the pivoted form 6 during the forming operation. To this end guide bars or levers 18 are fulcrumed on pins 19 secured in the main frame and these levers have cam faces 18*a* and 18*b* 130

at their upper ends which are engaged by the rollers 11 during the downward movement of the pivoted forming members causing the pivoted forming members 6 to swing inward 5 ly toward the opposite faces of the rib 4 of the fixed form during the forming operation. For giving a final set to the bends at the base of the reentrant baffle, means are provided to exert a direct inward pressure upon the 10 rollers 11 to force the forming faces 6b of the pivoted member 6 against the opposite side faces of the rib 4. To this end the levers 18 carry cam rollers 20 at their lower ends journaled on pins 21 fixed to the levers, these 15 rollers being engaged simultaneously by a double cam 22 carried by the drive shaft 2 at the end of the forming movement.

In the operation of the machine a sheet S is laid upon the fixed form 1a immediately 20 beneath the movable forming members as shown in Fig. 4 of the drawings. Upon operation of the drive shaft 2 the shaft 7 and with it the pivoted forming members 6 are moved downwardly by means of the connecting links 13. At the beginning downward movement the inner lower corners between the forming portions 6a and 6b of the pivoted forming members 6 engage with the sheet along the bending lines *m* and during 25 the first portion of the downward movement the rollers 11 travel along the vertical guides 1b so that the forms 6 move straight down until the sheet S is brought into engagement with the upper edge of the rib 4 of the fixed 30 form. During this initial movement the sheet S is bent slightly about the lines *m*, since the upper edge of the rib 4 is below the opposite edges of the form 1a, the sliding member 5 during this initial movement 35 following the sheet by gravity. The parts will now be brought to the positions indicated in Fig. 5 of the drawing in which the sheet S rests upon opposite edge portions of the form and upon the top edge of the central rib thereof. In this position the rollers 40 11 of the pivoted forming members 6 are at the upper ends of the cam portions 18a of the levers 18 and the eccentrics 17 are in a position to begin to exert a downward pressure 45 upon the hooks 16 and through the hooks 16 upon the sliding forming member 5. The sliding member 5 has a concavity along its bottom conforming in shape to the shape of the peak of the rib 4 of the fixed form. 50 Downward movement of the sliding form 5 serves to bend the sheet S over the top of the rib 4 to the shape of the upper edge of the rib 4. The cams 18a have a curvature such that during the downward movement of the 55 pivoted forming members 6, the edges thereof will be maintained in contact with the sheet S along the bend lines *m* throughout the bending movement of the sheet about the bend line *n* at the peak of the rib 4. As 60 the movable forming parts move downward- 65

ly toward the position shown in Fig. 1 of the drawings, the sheet S is bent simultaneously along the two lines *m* and along the line *n* midway between the lines *m*. The cam surfaces 18a do not guide the pivoted members to the full extent of their inward movement for the reason that as the rollers 11 approach their lowest positions, the cam surfaces 18a get so flat as to practically lock the downward movement. To overcome 70 this difficulty, the rollers 11, as the members 6 approach the end of their downward movement roll off the surfaces 18a onto surfaces 18b and at the same instant, the double cams 22 come into engagement 75 with the rollers 20 at the lower ends of the levers 18 pushing the rollers 20 outwardly 80 and swinging the levers 18 inwardly about their pivots to exert a direct thrust against the outer sides of the rollers 11 pushing the pivoted members 6 inwardly about their pivot to compress the sheet between the base 85 portions of the ribs 4 and against the form 1a adjacent the bends. During these final movements, the main links 13, the eccentrics 90 17 and the double cams 22 are all turned into approximately dead center positions so that very heavy pressures are applied in the proper directions to give the metal the set that is necessary at the bends. To accommodate 95 the indented holes 3 in the body of the sheet, those portions of the form which would otherwise engage and exert pressure on the perforated areas are recessed or depressed to the amount of the indentation as indicated at 1d and 4a in Fig. 4. The indentations 1d in the cylindrical portion of the fixed form and 4a at the sides of the rib 4 thereof provide spaces in which the indentations lie during the forming operation and prevent any pressure being exerted upon the 100 perforated portions of the sheet which would tend to flatten or iron out the indentations, the forming pressure being exerted upon the sheet only along the unperforated strips 105 where the lines of bend occur and along the side edges of the sheet. If desired, flanges 110 may be turned up along the edges of the sheet at the portions thereof which form the side walls of the baffle and such flanges will lie outside of the forming members 6 and will not be distorted during the forming operation.

On continued movement of the drive shaft 2 from the position shown in Fig. 1 of the drawings, the eccentrics 17 will turn off of the hook links 16, thus freeing these links. At the same time cam faces 15a made a part of the arms 15 will engage rollers 23 carried by pins 24 secured to the links 16 pushing these 120 links over against stops 1c projecting out from the main frame thus freeing the hook 16 from the eccentric 17 so that it will clear the eccentric during its upward movement. Further turning of the arm 15 will raise the roller 125 130

23 until it rests upon a circular engaging portion 15b so that the hook is free to be raised. At the same time the double cam moves out of engagement with the rollers 20, freeing the levers 18 and allowing the pivoted forming members 6 to open under the action of the springs 10. All parts are now released and the crank arm 15 acting upon the links 13 will raise the upper shaft 7 carrying the 10 pivoted forming members 6 to their uppermost position, at the same time raising the sliding form 5 through the straps 9. When the movable parts have been raised to their uppermost positions, the roller 23 will be 15 out of contact with the cam on the arm 15 so that the hook links will swing by gravity to vertical position ready to be again engaged by the eccentrics 17.

Having described my invention, I claim—

20 1. The method of forming perforated sheet metal articles which have portions with relatively sharp bends, which comprises perforating a sheet to provide perforated areas with relatively narrow unperforated strips 25 lying between the perforated areas and subjecting the sheets to pressure between forming members engaging the sheets along the unperforated strips only.

20 2. The method of forming perforated sheet 30 metal articles having relatively sharp bends which comprises perforating the major portion of a flat sheet leaving unperforated a strip along a line of bend and along the edges of the sheet, bending the sheet along the un- 35 perforated portion, holding the unperforated edges of the sheet thereof against angularly disposed walls of a form conforming to a portion of the article being formed and applying pressure to the unperforated portions 40 of the sheet to give the metal a permanent set to the shape of the form.

3. The method of forming sheet metal articles having relatively sharp bends and flanged perforations in the body thereof, 45 which comprises forming flanged perforations throughout the sheet except in strips along the edges and along lines of bend, bending said sheet to the shape of the article being formed between forming members engag- 50 ing the sheet along the unperforated portions only of the sheet.

4. The method of forming a ribbed perforated sheet metal article having closely spaced perforations, which comprises forming closely spaced perforations throughout all of a flat sheet except along narrow strips at the edges and along lines where the bends at the bases and peaks of the ribs occur, and forming the article by subjecting the sheet to 60 pressure between forming members which engage with the sheet only along the unperforated strips.

5. The method of forming a ribbed sheet metal article having closely spaced flanged perforations which comprises forming closely

spaced flanged perforations throughout the body of a flat sheet leaving unperforated strips along the edges and along lines where the bends at the bases and peaks of the ribs occur, and forming the ribs and intermediate 70 body portions of the article by subjecting the unperforated portions of the sheet to pressure between forming members.

6. The method of forming a ribbed sheet metal cylinder having closely spaced flanged 75 perforations, which comprises forming closely spaced flanged perforations throughout the entire body of a flat sheet except along narrow strips at the edges and along lines where the bends at the bases and peaks of the ribs occur, and forming the ribs and intermediate 80 cylindrical body portions of the cylinder by subjecting the sheet to pressure between forming members engaging only the unperforated strips of the sheet. 85

7. The method of forming a sheet metal cylinder having integral reentrant portions from a substantially flat piece of sheet metal which comprises subjecting successive sections of the sheet successively to a bending 90 operation in which a portion of the section acted upon is bent to form the reentrant portion and the remainder thereof is bent to cylindrical form.

8. The method of forming a sheet metal 95 cylinder having integral reentrant portions extending longitudinally thereof from a substantially flat piece of sheet metal, which comprises bending successive portions of the sheet successively upon a form shaped to conform 100 to a segment of the wall of the cylinder and to a reentrant portion thereof.

9. The method of forming a sheet metal cylinder having integral reentrant portions and closely spaced perforations in both the 105 cylindrical body portions and the reentrant portions, which comprises forming closely spaced perforations in the sheet leaving strips unperforated along the lines of bend in the portions of the sheet which are to 110 form the reentrant portions of the cylinder, bending the sheet by applying pressure between bending formers to the unperforated strips while holding the perforated portions 115 between members conforming to the inner and outer surfaces of the cylinder.

10. The method of forming a sheet metal cylinder with integral reentrant portions forming baffles which comprises bending said sheet over a form which has a longitudinally 120 extending rib conforming to the outer surface of the reentrant baffle portion of the cylinder and a cylindrical portion at one side of the rib simultaneously bending the sheet with relatively light pressure over the edge of the rib and along a parallel line which when the sheet is folded against the face of the rib will lie at the base thereof and finally applying heavy pressure upon the sheet 125 simultaneously against the upper edge of 130

the rib, against the side face of the rib adjacent the base thereof.

11. The method of forming a sheet metal cylinder having integral reentrant portions 5 and closely spaced flanged perforations in both the cylindrical body portion and the reentrant portions, which comprises forming flanged perforations in a flat sheet leaving strips unperforated along the edges and along 10 the lines of bend in the portions of the sheet from which the reentrant portions are formed, bending said sheet by engaging the same and exerting pressure along the lines of bend only, and imparting a permanent 15 set at the bends by subjecting the portions of the sheet at the bends to heavy pressure between forming members and at the same time forming the intermediate perforated portions by pressing the edge portions there- 20 of between forming members.

12. The method of forming ribbed sheet metal articles having perforations in the body portions and in the ribs thereof which comprises forming perforations in a flat sheet 25 leaving strips unperforated along the edges and along the lines of bend in the portions of the sheet from which the ribs are formed, bending the sheet by clamping the same along the line of bend lying at the peak of a rib, 30 engaging the sheet along the lines of bend lying at the base of the ribs, restraining the movement of the portion of the sheet outside the lines of bend, and applying pressure to form the bends, and imparting a permanent 35 set to the ribs and body portions of the article by applying heavy pressure between forming members to the unperforated portions of the sheet.

13. The method of forming ribbed sheet 40 metal articles from flat sheets which comprises clamping the sheet along a line of bend between forming members, engaging said sheet with movable forming members having a line engagement with the sheet on opposite 45 sides of the line on which the sheet is clamped, exerting pressure on the movable forming members to bend the sheet along the peak line of the rib, maintaining the line engagement of the movable forming members with the 50 same portions of the sheet during the bending movement and restraining outer portions of the sheet to form bends along the lines engaged by the movable forming members.

14. Apparatus for forming a cylindrical 55 ribbed shell from sheet metal having perforated areas from which the cylindrical portions of the shell are formed and other perforated areas from which the side walls of the ribs are formed and relatively narrow 60 unperforated strips between the perforated areas, which comprises pressure applying forming devices adapted to apply pressure to the unperforated strips only to form relatively sharp bends therein to form the ribs, 65 and means for simultaneously bending ad-

jacent perforated areas to cylindrical form.

15. Sheet metal forming apparatus comprising a concave form having an intermediate upstanding rib, a member co-operating therewith to clamp a sheet upon the peak of 70 said rib, and a pair of sheet engaging members having edges adapted to have a line engagement with the sheet on opposite sides of the rib, each member of said pair having faces on opposite sides of its engaging edge 75 adapted to conform to a side of the rib and to the concave form, and means for moving said last mentioned members toward the base of the rib and toward opposite sides of the rib.

16. Sheet metal forming apparatus comprising a rigid concave form having an intermediate upstanding rib, and a plurality of co-operating movable formers, one of the 80 movable formers being adapted to clamp the sheet against the peak of the rib of the rigid form and other of said formers being movable toward the rigid form and toward opposite faces of the rib and adapted to fit within the form on opposite sides of the rib. 85

17. Sheet metal forming apparatus comprising a rigid form having an intermediate upstanding rib and cylindrical face portions on opposite sides of the rib, and means co-operating with said rigid form to hold the 90 sheet against the top of the rib and to bend the sheet over the rib and into conformity with the rib and cylindrical face portions of the rigid form. 95

18. Sheet forming apparatus comprising 100 means for clamping a sheet along a given line, pressure applying members adapted to engage the sheet along lines a predetermined distance from the clamping line and to apply pressure to the sheet to bend the same 105 about the clamping line, means for restraining the movement of the sheet to cause the same to bend along the lines engaged by the pressure applying members, and means for maintaining the pressure applying members 110 in line engagement with the sheet along the same lines throughout the bending movement of the sheet. 115

19. Sheet forming apparatus comprising a 120 form having a concave forming face and an intermediate rib extending out from the face, a pressure applying member movable toward and from the peak of the rib, and a pair of pressure applying members movable toward the face of the former and toward the side faces of the rib, each member of said pair being adapted to fit against the side of the rib and against the concave face of the form at one side of the rib. 125

20. Sheet forming apparatus comprising a 130 form having a concave face with an intermediate projecting rib, a pressure applying member movable toward and from the peak of the rib, a pair of pressure applying members having convex faces corresponding in

curvature to the concave faces of the form and inner faces corresponding to the outer faces of the rib, and means for moving all said pressure applying members simultaneously toward the form and said pair of pressure applying members toward the opposite faces of the rib.

21. Sheet metal forming apparatus comprising means for clamping a sheet along a fixed bending axis, pressure applying members adapted to engage the sheet along bending axes on opposite sides of the fixed bending axis, means for moving said pressure applying means to bend the sheet about the fixed axis and for maintaining said pressure applying members in engagement with the sheet along the bending axes during the bending movement, and means for restraining the movement of portions of the sheet on opposite sides of the bending axes to cause the sheet to bend along said axes.

22. Sheet metal forming apparatus for forming ribbed articles comprising a set of relatively movable sheet forming members which when brought together upon a portion of a sheet confine the same to the configuration of a rib and adjacent body portions of the article, said forming members having raised marginal portions adapted to engage the sheet so confined along the edges and along the lines of bend at the base and peak of the rib.

23. A sheet metal forming machine comprising a fixed form, having a projecting rib, a set of forming members movable toward and from the fixed form, said set comprising a sliding member movable toward and from the peak of the rib, a second sliding member movable independently of said first mentioned sliding member and a pair of forming members pivoted to said second sliding member, and means for swinging the pivoted forming members toward the opposite faces of the rib during their movement toward the form.

24. A sheet metal forming machine comprising a fixed form having angularly disposed forming surfaces, means co-operating with a portion of the fixed form to clamp a sheet along a bending axis adjacent an edge of one of said angularly disposed surfaces, a bending member movable toward and from the form, an operating shaft, means for operating the clamping member from the shaft, means operated by the shaft for moving the bending member toward one of the angularly disposed surfaces of the form, a guide member for guiding the bending member during its movement toward said last mentioned surface toward the other surface, and a cam on the shaft acting on said guide member at the end of its movement to exert pressure thereon to give a permanent set to the metal of the bend.

25. A sheet metal forming machine com-

prising forming members adapted to engage a sheet simultaneously along a plurality of parallel lines, means for moving certain of said forming members relatively to other of said forming members and for restraining the movement of portions of the sheet to cause the sheet to be bent along the lines of engagement, means for imparting an additional movement to certain of the forming members to maintain them in engagement with the sheet along the bending lines during the bending movement of the sheet, and means operable at the end of the bending movement to compress the sheet at the bends.

In testimony whereof, I hereunto affix my signature.
